UNITED STATES PATENT OFFICE

THOMAS HAVELOCK KINGSTON, OF WEST SOMERVILLE, MASSACHUSETTS, ASSIGNOR
TO BUILDERS' PATENT SCAFFOLDING COMPANY, A PARTNERSHIP COMPOSED OF
FRANK G. KINGSTON, A. R. KINGSTON, C. C. PIMM, AND MABEL G. KITCHEN, OF
WEST SOMERVILLE, MASSACHUSETTS

PUTLOG

Application filed March 5, 1929. Serial No. 344,506.

My invention relates to putlogs and an object is to provide a clincher plate connection or attachment with the putlog end which will have in one or another form or embodiment of the invention adaptability or flexibility in application to the putlog and in the performance of its functions without any impairment of that strength and efficiency which are so important because human life and limb are concerned.

My invention consists in whatever is described by or is included within the terms or scope of the appended claims.

In the drawings:—

Fig. 1 is a perspective view of a swiveled type of putlog attachment embodying my invention;

Fig. 2 is a detail view in vertical section of a clamp used when the attachment is detachable;

Fig. 3 is a vertical section of another embodiment of my invention in which the clincher plate is swiveled;

Fig. 4 is a perspective view of a fragment or portion of a clincher plate attachment which is non-swiveling.

In all the embodiments of my invention shown in the drawings, the clincher plate is substantially an inverted L-shape and comprises the horizontal blade-like member, 10, that is sufficiently thin to be inserted in the joint or space between two bricks in a wall and the vertical shank member, 11, these two members being integral. The brick-engaging or bearing member has as is usual at its outer end a hook, 12, to catch over the inner side of the brick on which the member, 10, rests. Also in each case the shank, 11, is situated between similar brackets, 13, which lie flat against the shank on each side thereof, the three being rigidly secured together as by rivets, 14. There are thus three plies or layers of metal plates at the shank portion of the clincher which makes an exceedingly strong and rigid construction. Each bracket, 13, at top and bottom of its vertical member has an integral outturned lug or foot, 15, so that at top and bottom of the clincher member there are horizontal outwardly projecting feet. Lying over the feet at the top is a horizontal plate, 16, and extending beneath the feet at the bottom is a similar horizontal plate, 16, the plate and foot in each case being rigidly united by rivets, 17.

In the embodiment of my invention shown in Figs. 1 and 3 the clincher plate, 10, is pivoted to swing horizontally, so that the putlog body which extends from the face of the building outward may stand at right angles to such face or at various oblique angles to

suit the requirements of the scaffolding having reference to the angular positions of the building walls exemplified in my Patent No. 1,077,839 of November 4, 1913. To secure that result the upper and lower plates, 16, have pintles or pivots, 18, that may be integral with the plate which project through pivot holes in an overlapping plate, 19, which constitutes a clip to bear against the top or bottom, as the case may be, of the putlog body, 20, at one end thereof, which body may be of wood or metal preferably of some structural shape, the pivoted shank portion of the clincher plate being of course, sufficiently spaced beyond the end of the body as to allow horizontal swinging with reference to the body through substantially 180°. Preferably each clip, 19, has a narrow vertical flange, 21, to overlap the side of the putlog body.

In the embodiment of my invention shown in Fig. 1, the device is not intended to be permanently connected with the putlog body. In this case the device exists in the form of an attachment so that it will be assembled with the proper body at the job, this making for advantage in shipment or transportation since it makes unnecessary the shipment of the complete putlog including a body. For that reason an inverted U-shape strap or loop, 22, as best shown in Fig. 1 is provided which straddles the two clips, 19, and is rigidly secured to one of them (top one) by a rivet, 23; below the other clip, 19, is a cross-bar, 24, which at its ends is passed through holes in the legs and the projecting part upset or riveted, and at the transverse center of said cross-bar, 24, is a vertical threaded hole through which passes a clamp screw, 25, adapted to bear against the underside of the lower clip, 19, and caused to exert a clamping

pressure which draws the two clips, 19, with clamping force against the interposed end portion of the putlog body, 20. By unscrewing the clamp screw, 25, the pressure is released sufficiently to permit the withdrawal 5 of the attached device from the putlog body. The clamp screw, 25, has a radial handle, 26, for turning it.

In the embodiment of my invention shown 10 in Fig. 3, the connection between the clips, 19, and the putlog body, 200, is made by a bolt, 27, which passes through a vertical hole bored in the body, 200, and through alining holes in said clips, so that a permanent attachment 15 of the device to the putlog body may be had.

In the embodiment of my invention shown 20 in Fig. 4, the clincher plate is not pivoted or swiveled, but is rigidly fixed in one position in which it extends parallel with the length of the putlog body, and the clips, 19, are similar to those of Fig. 1 and a clamping device similar to that shown in Figs. 1 and 2 is employed for the ready detachable connection 25 of the device with a putlog. Of course, a permanent connection can be made with the putlog just as is done in the case of the embodiment shown in Fig. 3.

What I claim is:

- 30 1. A putlog wall-engaging member having a shank, vertical brackets secured to the shank sides having laterally extending feet, and plates above and below the feet, and connected therewith.
- 35 2. A putlog wall-engaging member having a shank, vertical brackets secured to the shank sides having laterally extending feet, and plates above and below the feet, and connected therewith, and means to secure said plates to a putlog body.
- 40 3. In combination with a putlog wall-engaging member, a pair of opposite clips connected therewith, each clip having a plate-like portion to lie upon a side of a putlog body and flanges to overlap other body sides and means to secure said clips to a body.
- 45 4. A putlog wall-engaging member having means for attachment to a body comprising opposite body-engaging members, at least one being a plate to lie over one surface of the body, and having marginal flanges to overlap surfaces of the body at right angles to the plate-engaging surface, and screw clamp means acting simultaneously on said opposite body-engaging members.

In testimony whereof I hereunto affix my signature.

THOMAS HAVELOCK KINGSTON.
